CLOSURE FOR RECEPTACLES

Percy M. Thorn, New Rochelle, N. Y.

Application August 10, 1936, Serial No. 95,102

9 Claims. (Cl. 221—64)

This invention relates to a closure such as cans, bottles and the like.

It is an object of this invention to provide a simple closure having a peripheral opening which will maintain a tight closure under all conditions.

It is a further object to provide a device of the character described which will be inexpensive in manufacture and reliable in operation.

Other objects of the invention will in part be obvious and will in part appear hereinafter.

The invention accordingly comprises an article of manufacture possessing the features, properties, and the relation of elements which will be exemplified in the article hereinafter described and the scope of the application of which will be indicated in the claims.

For a fuller understanding of the nature and objects of the invention, reference should be had to the following detailed description, taken in connection with the accompanying drawing, in which:

Figure 1 is a top plan view partly in section of a device embodying this invention in the closed position.

Figure 2 is a central longitudinal section thereof.

Figures 3 and 4 are similar to Figures 1 and 2, save that the closure is in the open position.

Figures 5, 6, 7, and 8 are similar to Figures 1, 2, 3, and 4, but disclosing a somewhat modified construction.

In the drawing the numeral 10 designates a base having a circumferential wall 11 and an end wall 12. The end wall 12 is substantially flat and is provided with an opening 13 in its peripheral portion. A cap 14 is mounted for rotation upon the base in any practical manner, as for example, as illustrated, there is provided upon the circumferential wall of the base a bead 15 fitting into a mating bead 16 upon the cap. The cap has an end wall 17 parallel to the end wall 12 and spaced from it, and also provided with an opening 18 of size, shape and position corresponding to the opening 13. Between the end walls 12 and 17, there is mounted a sectoral shutter 19 arranged for rotation about the axis of the base, as for example, by being provided with a depression 20 fitting into a depression 21 in the base. This shutter is also provided with an opening 22 corresponding in size, shape and position to the opening 13. A pin 23 is carried by the end wall 17 of the cap 14 in position to engage the edges of the sectoral shutter when the cap is rotated upon the base, but by reason of the fact that the cap in the form illustrated in Figure 1 occupies only

about 240° of the circumference, a lost motion is provided between the pin and the shutter so that the pin will not engage the shutter to turn it until the cap has been rotated far enough to bring the opening 18 of the cap and the opening 22 of the shutter out of registry. Thereafter a further rotation of the cap will move the shutter to bring the opening 22 out of registry with the opening 13.

In order to insure a tight closure between the shutter and the base, a washer of cork or the like, designated at 24, is inset into the depression 25 in the base entirely surrounding the opening 13 so that the pressure between the shutter and the base caused by the cap is localized in the area 15 immediately surrounding the opening to afford a tight joint. In order further to provide against the possibility of tilting of the shutter, the end wall 12 has a raised portion 26 at the axis.

Means are also provided for limiting the motion of the shutter to that required for the closure which may take the form of a pin 27 extending upwardly from the base to engage the edges of the shutter and so positioned that the shutter is free to move between its open and closed position but cannot move further.

The form of the invention as illustrated in Figures 5, 6, 7, and 8, is similar to that shown in Figures 1, 2, 3, and 4, except that as here illustrated, the openings 13a, 22a and 18a are of considerably less circumferential extent than in the form first shown, and there is provided on the periphery of the device an annular raised portion 28 to prevent tilting of the shutter to one side of the other as the cap is rotated.

In this construction, moreover, instead of providing the washer 24a to effect a tight joint between the base and the shutter there is provided a raised portion 29 completely surrounding the opening 13a to take the pressure between the shutter and the base in a manner to afford a tight closure.

Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the

invention, which as a matter of language, might be said to fall therebetween.

Having described my invention, what I claim as new and desire to secure by Letters Patent is:

5 1. A closure for containers and the like comprising a base, a cap rotatable on the base and a shutter rotatable between the cap and the base about the axis of the cap, a pin upon the cap adapted to engage the shutter, there being openings between the periphery and the center of said cap, said shutter and said base in position to be in registry in one position of the parts, there being lost motion between the pin and the shutter whereby the rotation of the cap will bring all of 10 the openings out of registry with each other, said base having a raised portion immediately surrounding said opening in constant contact with said shutter in all positions of the latter so that pressure between the shutter and the base 15 is localized both in the open and in the closed 20 positions.

2. A closure for containers and the like comprising a base, a cap rotatable on the base and a shutter rotatable between the cap and the base about the axis of the cap, a pin upon the cap adapted to engage the shutter, there being openings between the periphery and the center of said cap, said shutter and said base in position to be in registry in one position of the parts, there being lost motion between the pin and the shutter whereby the rotation of the cap will bring all of the openings out of registry with each other, said base having a raised portion immediately surrounding said opening in constant contact with said shutter in all positions of the latter so that pressure between the shutter and the base is localized both in the open and in the closed positions, there being also a raised portion at the axis of the shutter so that the shutter is 30 kept parallel to the plane of the raised portion.

3. A closure for containers and the like comprising a base, a cap rotatable on the base and a shutter rotatable between the cap and the base about the axis of the cap, a pin upon the cap adapted to engage the shutter, there being openings between the periphery and the center of said cap, said shutter and said base in position to be in registry in one position of the parts, there being lost motion between the pin and the shutter whereby the rotation of the cap will bring all of the openings out of registry with each other, said base having a raised portion immediately surrounding said opening in constant contact with said shutter in all positions of the latter so that pressure between the shutter and the base is localized both in the open and in the closed positions, there being also a raised portion at the axis of the shutter so that the shutter is kept parallel to the plane of the raised portion, and a raised peripheral portion on the base portion on each side of the opening on which the edges of the shutter may ride as the shutter is moved.

4. A closure for containers and the like comprising a base, a cap rotatable on the base and a sectoral shutter rotatable between the cap and the base about the axis of the cap, a pin upon the cap adapted to engage the edges of said shutter, there being openings between the periphery and the center of said cap, said shutter and said base in position to be in registry in one position of the parts, there being lost motion between the pin and the shutter whereby the rotation of the cap will bring all of the openings out of registry with each other, said base having a raised portion immediately surrounding said opening in

constant contact with said shutter in all positions of the latter so that pressure between the shutter and the base is localized both in the open and in the closed positions, and means upon the base to limit the rotation of the shutter.

5 5. A closure for containers and the like comprising a base, a cap rotatable on the base and a sectoral shutter rotatable between the cap and the base about the axis of the cap, a pin upon the cap adapted to engage the edges of said shutter, there being openings between the periphery and the center of said cap, said shutter and said base in position to be in registry in one position of the parts, there being lost motion between the pin and the shutter whereby the rotation of the cap will bring all of the openings out of registry with each other, said base having a raised portion immediately surrounding said opening in constant contact with said shutter in all positions of the latter so that pressure between the shutter and the base is localized both in the open and in the closed positions, and means upon the base to limit the rotation of the shutter, there being also a raised portion at the axis of the shutter so that the shutter is kept parallel to the plane of the raised portion.

6. A closure for containers and the like comprising a base, a cap rotatable on the base and a sectoral shutter rotatable between the cap and the base about the axis of the cap, a pin upon the cap adapted to engage the edges of said shutter, there being openings between the periphery and the center of said cap, said shutter and said base in position to be in registry in one position of the parts, there being lost motion between the pin and the shutter whereby the rotation of the cap will bring all of the openings out of registry with each other, said base having a raised portion immediately surrounding said opening in constant contact with said shutter in all positions of the latter so that pressure between the shutter and the base is localized both in the open and in the closed positions, and means upon the base to limit the rotation of the shutter, there being also a raised portion at the axis of the shutter so that the shutter is kept parallel to the plane of the raised portion, and a raised peripheral portion on the base portion on each side of the opening on which the edges of the shutter may ride as the shutter is moved.

7. A closure for containers and the like comprising a base, a cap rotatable on the base and a shutter rotatable between the cap and the base about the axis of the cap, a pin upon the cap adapted to engage the shutter, there being openings between the periphery and the center of said cap, said shutter and said base in position to be in registry in one position of the parts, there being lost motion between the pin and the shutter whereby the rotation of the cap will bring all of the openings out of registry with each other, said base having a resilient washer immediately surrounding said opening so that pressure between the shutter and the base is localized.

8. A closure comprising inner and outer disks, the outer disk having a limited turning movement relative to the inner disk, a segmental shutter disk located between the inner and outer disks and having pivotal or rotary mounting concentric with said disks, all of said disks having openings therein, and means on the outer disk adapted to engage opposite ends of the shutter disk whereby the turning movement of the outer disk in opposite directions causes the shutter disk to

move likewise in opposite directions to cause said openings to be registered or to be cut off.

9. A closure of the character described including an inner disk having an opening at one side of its center, a shutter disk concentrically mounted to turn on the inner disk, an outer disk above the shutter disk, said outer and shutter disks having openings therein of the same size and

shape as the opening in the inner disk, said shutter disk constituting a segment, and an inwardly projecting pin on the outer disk in position to engage the edges of said segment to cause the shutter disk to turn and move in opposite directions and move its opening into and out of register with the openings in the other disks.

PERCY M. THORN.
